UNITED STATES PATENT OFFICE.

JAMES A. FARLOW AND JOHN STRAYER, OF BROOKLYN, NEW YORK.

CAR-FENDER.

SPECIFICATION forming part of Letters Patent No. 595,379, dated December 14, 1897.

Application filed June 18, 1897. Serial No. 641,326. (No model.)

To all whom it may concern:

Be it known that we, JAMES A. FARLOW and JOHN STRAYER, citizens of the United States, residing at Brooklyn, in the county of Kings and State of New York, have invented certain new and useful Improvements in Fenders or Guards for Tramway-Cars, of which the following is a full and complete specification, such as will enable those skilled in the art to which it appertains to make and use the same.

This invention relates to fenders or guards for tramway-cars; and the object thereof is to provide an improved device of this class which is constructed and connected with the car in such manner that it will always be suspended at the same distance from the ground or the rails of the track, no matter how much the end of the car be depressed.

The invention is fully disclosed in the following specification, of which the accompanying drawings form a part, in which—

Figure 1 is a side view of the end of a car provided with our improved fender or guard, and Fig. 2 a bottom plan view thereof.

In the drawings forming part of this specification the separate parts of our improvement are designated by the same numerals of reference in each of the views, and in said drawings we have shown at 5 a portion of the end of a car which is provided with a platform 6 and a dashboard 7, and we also show a portion of the truck-frame at 8, and springs 9 by which the car is supported thereon.

The platform 6 is provided at about the middle thereof with hangers 10, the lower ends of which are yoke-shaped in form, as shown at 11, and pivotally connected with the side of the truck-frame 8 at 12 are yokes 13, which are held in vertical position, and the lower sides of these yokes are longer than the upper sides and are provided with pins 14, which rest in the lower yoke-shaped ends of the hangers, and the upper sides of said yokes are pivotally connected with rods or bars 15, and to each side of the platform, at the front end thereof, are secured longitudinal hangers 16, each of which is provided with two hanging links or bars 17, which are pivotally connected therewith and to the lower ends of which are pivotally secured keepers 18. The rear link or bar 17 on each side is also pivotally connected with the adjacent rod or bar

15, and we also provide a fender or guard frame 19, which consists of a rectangular frame composed of a rod 20, bent into the 55 form shown in the drawings, and the body portion of which is composed of wire or similar material, as shown at 21, and the frame of said fender or guard is bent upwardly and backwardly, and provided with backwardly-directed arms or extensions 22, which pass into the keepers 18, and are secured therein, and the normal position of the fender or guard is shown in Fig. 1, in which position the forward part of the fender or guard frame 65 is supported just above the rails of the track.

If at any time the end of the car be depressed by means of great weight therein or by reason of the car passing over a rough track when ordinarily loaded, the front platform will be 70 depressed, and the hangers 10 will operate on the yokes 13 to depress the lower sides and project the upper sides thereof forward, and this operation will project the bars 15 in the forward direction, and by means of the method 75 of connecting the fender or guard frame with the hangers 6 said fender or guard frame will be correspondingly projected and raised above the track, and when the end of the car returns to its normal position the said fender 80 or guard frame will also return to the position shown in Fig. 1, and the operation will always be automatic, the fender or guard frame being always held at the same distance 85 above the rails of the track.

Our improved fender or guard is simple in construction and operation, and is perfectly adapted to accomplish the result for which it is intended.

Having fully described our invention, we 90 claim as new and desire to secure by Letters Patent—

1. In a fender or guard for tramway-cars, the combination with the end of the truck-frame, of yokes pivoted to the sides thereof, the sides 95 of which are directed forwardly, hangers connected with the platform of the car, and pivotally connected with the lower sides of said yokes, rods pivotally connected with the upper sides of said yokes, and extending forwardly, hangers connected with the forward end of the platform of the car at the opposite sides thereof, links or bars pivotally connected with said hangers at each side, and

with a fender or guard frame support, one of said last-named links or bars at each side being pivotally connected with said yokes, and a fender or guard frame pivotally connected 5 with said supports, substantially as shown and described.

2. The combination with the platform of a car, of a fender or guard frame suspended therefrom by means of pivoted links or bars, 10 yokes pivotally connected with the sides of the truck-frame, the separate sides of which are directed forwardly, hangers suspended from the platform of the car, and pivotally connected with the lower sides of said yokes,

and rods which are pivotally connected with 15 the upper sides of said yokes, and with the suspending devices of the fender or guard frame, substantially as shown and described.

In testimony that I claim the foregoing as my invention I have signed my name, in presence of the subscribing witnesses, this 16th day of June, 1897.

JAMES A. FARLOW.
JOHN STRAYER.
